UNITED STATES PATENT OFFICE.

ERNST H. HUENEFIELD, OF CINCINNATI, OHIO.

WOOD-BURNING STOVE.

SPECIFICATION forming part of Letters Patent No. 601,565, dated March 29, 1898.

Application filed July 20, 1897. Serial No. 645,240. (No model.)

To all whom it may concern:

Be it known that I, ERNST H. HUENEFIELD, of Cincinnati, in the county of Hamilton and State of Ohio, have invented certain new 5 and useful Improvements in Wood-Burning Stoves; and I do hereby declare the following to be a full, clear, and exact description of the invention, such as will enable others skilled in the art to which it appertains to 10 make and use the same.

My invention relates to an improvement in wood-burning stoves, the object of the invention being to provide a heater of simple and economical construction and one in which the 15 fire-pot or cylinder and outer jacket are so located with relation to each other as to provide for the free and uniform circulation of air within the heating-space between the fire-pot and cylinder.

With these ends in view my invention consists in the parts and combinations of parts, as will be more fully described, and pointed out in the claims.

In the accompanying drawings, Figure 1 is a view in elevation of a stove embodying my invention. Fig. 2 is a view in horizontal section thereof. Fig. 3 is a view in vertical section taken through the front and rear of the stove, and Fig. 4 is a view in plan.

A represents the outer jacket, preferably rectangular longitudinally and square transversely. This jacket is made of suitable sheet metal and surrounds and contains the cylindrical fire-pot B. This fire-pot is retained equidistant from the sides of the outer jacket by the spacing-braces a at the bottom and by the draft-flue and by the spacing-collars connecting the two parts at the fuel or feeding opening C and the smoke-flue or off-take D. The fire-pot is closed tightly at its base, which terminates in a plane slightly above the lower end of the outer jacket and is closed at all points except at the point of attachment of the draft-flue and fuel and smoke openings.

The upper end or the fire-pot terminates slightly below the top of the outer jacket, and hence it will be seen that the air entering the base of the stove passes up between the outer jacket and inner fire-pot, becomes highly heated, and escapes from the space at

the four corners of the top, which is perforated at these points for the escape of the hot air. By making the outer jacket square and the fire-pot cylindrical air-spaces of considerable size are formed at the four corners and the air rises in large volumes, while the spaces between the corners are considerably reduced in width and hence operate to rapidly heat the air passing up at these points. 55 By providing the fire-pot or inner cylinder with a top E removed from the top E' of the outer jacket an air-space between the latter is formed, which absolutely prevents the top E' from becoming overheated, as it would do 60 if it formed the top of the fire-pot also. 65

The stove rests on legs F, which elevate the outer jacket sufficiently above the floor to permit of the free passage of air upwardly and around the fire-pot. 70

The draft-flue G comprises a square or rectangular cast frame H, adapted to rest between the fire-pot and outer jacket, the edge or end adjacent to the fire-pot being curved to conform to the shape of the portion of the 75 fire-pot against which it abuts, while the outer end, which consists of a removable plate I, held in the frame H by screws, rests against the inner face of the jacket and is secured thereto by the screws d, which secure the 80 damper-plate in place. From this it will be seen that this draft-flue, in addition to supplying air to the fire-pot, also serves as a brace to stiffen the fire-pot and jacket and a spacing-block to hold them in their proper relative positions. The rear concave face h of the frame H is provided near its lower end with an opening h', which corresponds with a similar opening in the fire-pot. The edges of the opening in the fire-pot are reinforced 85 by the cast-metal frame K, which latter is held in place by the bolts k, passing through said frame and through the fire-pot and rear wall or face of the frame H. This frame K protects the sheet-metal opening from damage by contact with logs of wood thrown into the stove. The frame H is provided at its outer upper end with openings covered by the ornamental damper-frame J and closed by the damper J'. From this it will be seen 90 that the air passing through the damper-plate enters the hollow cast-metal frame H and

passes downwardly therein toward the lower end of the latter and from thence into the fire-pot for the purpose of supporting combustion.

The smoke-flue coupling connecting the top 5 of the fire-pot and the top of the outer jacket consists, primarily, of an oval cast-metal spacing collar or sleeve M, provided near its lower end with an integral flange m, which latter rests on the top E of the fire-pot B, the 10 lower end of sleeve passing through an opening in said top. This opening is reinforced by the cast-metal oblong ring m², which latter is secured in place by the bolts or screws m³. Resting on the flange m is the spacing-sleeve m⁵, having a flanged upper end, which latter rests against and supports the top of the outer jacket, the walls of the opening in top of the jacket being reinforced by the oblong cast-metal ring m⁴. These parts—to wit, 15 the two reinforcing-rings m² m⁴, the tops E and E', and the flange m—are all secured together by the two bolts or screws m³, and the sleeve M, top plate of the fire-pot, and reinforcing-ring m² are further secured together 20 by the bolts or screws m⁶. With this construction it will be seen that a practically air-tight joint is formed, thus preventing the escape of smoke at this point. In addition to this it braces the two tops and absolutely prevents any change in the relative positions of 25 said tops.

The feed or fuel opening of the stove comprises a spacing-ring L, flanged at its two ends, one flange resting on the top plate of the fire-pot and the other against the lower side of the top plate of the jacket. This ring is of the same diameter as the fuel-openings in the top plate of the jacket and fire-pot and is secured to both plates by the sheet-metal 30 clamping-ring L', which latter is located within the ring L and may be riveted thereto. This inner ring is flanged at both ends, the lower flange l' taking under the edge of the top plate of the fire-pot and clamping the ring 35 L to the fire-pot and the upper flange overlapping the top plate of the jacket and the flange N of the top ring N'. This top ring N' rests on the top of the jacket, and hence it will be seen that by turning down the upper 40 flange of the clamping-ring L' into the lower flange of the top ring the parts are clamped and held securely in proper relative positions. The top ring N' receives the hood O, which latter closes the fuel-opening in a practically 45 air-tight manner and prevents the ingress of air or the egress of smoke.

It is evident that many slight changes might be resorted to in the relative arrangement of parts herein shown and described without departing from the spirit and scope of my invention. Hence I would have it understood that I do not wish to limit myself to the exact construction of parts herein shown and described; but,

Having fully described my invention, what I claim as new, and desire to secure by Letters Patent, is—

1. In a stove, the combination with a fire-pot and a sheet-metal jacket, of a draft-flue interposed between the jacket and the pot and secured against the adjacent faces of both thus forming a brace and a spacing-block, an air-ingress opening through the jacket into the top of the flue, an air-egress opening from the bottom of the flue leading into the fire-pot, a damper-plate secured to the jacket and surrounding the air-ingress opening and a damper for closing the opening in the damper-plate, substantially as set forth. 70

2. In a stove, the combination with a fire-pot closed at its bottom and a sheet-metal jacket open at its bottom, of a draft-flue interposed between the jacket and pot and secured against the adjacent faces of both, thus acting as a brace and a spacing-block, air-ingress opening through the jacket into the draft-flue near the top of the latter, an air-egress opening from the flue near the base into the fire-pot and a damper for closing the inlet-opening to the flue, substantially as set 75 forth. 80

3. The combination with a sheet-metal fire-pot and a sheet-metal jacket, of the cast-metal draft-flue interposed between the jacket and pot, air-ingress opening near the top of the flue, air-egress opening near the base of the flue, a reinforcing-plate surrounding the draft-opening in the fire-pot, a damper-plate surrounding the air-ingress opening in the jacket and a damper. 85

4. The combination with a fire-pot and a jacket of a smoke-flue comprising a sleeve having a flange adapted to rest against the fire-pot, a spacing-collar resting on said flange and against the inner face of the jacket and bolts securing all of said parts together, substantially as set forth. 90

5. The combination with a fire-pot and a jacket, of a smoke-flue comprising a sleeve having a flange adapted to rest against the fire-pot, a spacing-collar resting on said flange and against the inner face of the jacket, a reinforcing-ring resting against the inner face of the fire-pot, a reinforcing-ring resting against the outer face of the jacket and bolts or screws connecting all of said parts. 100

6. The combination with a fire-pot and a jacket, of a sleeve, flanged at its upper and lower ends the lower flange adapted to rest under the top plate of the fire-pot and the top flange over the top of the jacket, a spacing-ring interposed between the two plates and clamping them to their respective flanges and a top ring secured under the top flange and projecting above the top plate, substantially 110 as set forth. 115

In testimony whereof I have signed this specification in the presence of two subscribing witnesses.

ERNST H. HUENEFELD.
